(57) **CLAIM**

The ornamental design for a free standing training bag with tripod base, as shown and described.

DESCRIPTION

FIG. 1 is a front elevation view of the free standing training bag with tripod base showing our new design;

FIG. 2 is a back elevation view thereof;

FIG. 3 is an exploded top perspective view wherein the detached plug element is visible between the tripod legs;

FIG. 4 is an elevation view rotated 60° from either FIGS. 1 or 2;

FIG. 5 is a top plan view thereof;

FIG. 6 is a bottom plan view thereof;

FIG. 7 is a an exploded bottom perspective view wherein the detached plug element is visible between the tripod legs as in FIG. 3;

FIG. 8 is an enlarged fragmentary view showing the top portion of the design;

FIG. 9 is an enlarged fragmentary view showing the central portion of the design; and,

FIG. 10 is a perspective view of the plug element shown separately for a clear and complete disclosure thereof.

1 Claim, 9 Drawing Sheets
